DELAY-ACTION FUSE.

1,343,415.

Specification of Letters Patent. Patented June 15, 1920.

Application filed October 5, 1917. Serial No. 194,847.

To all whom it may concern:

Be it known that we, FRANK DESMOND SPRAGUE and PHILIP WHALLEY ALLISON, citizens of the United States of America, 5 and residents of the city of New York, State of New York, have invented certain new and useful Improvements in Delay-Action Fuses, of which the following is a specification.

10 This invention relates to delay-action fuses for use in connection with projectiles. It is especially adapted to armor-piercing projectiles and it is in connection with this type of projectile that the invention will be 15 herein specifically described, but it is to be understood that this is merely for convenience and that the fuse has a wide adaptability by no means confined to armor-piercing work.

20 With this understanding, some of the main difficulties of armor-piercing shells should be appreciated in order that the special adaptability of this invention thereto may be comprehended. An armor-piercing 25 shell to be most effective against personnel or equipment should explode in the interior of the armored inclosure of which an armored vessel is the most common example. The armor-plate employed on armored vessels is of varying thicknesses and the retardation of the shell by the armor is correspondingly variable. Time fuses, or fuses 30 operating on the principle of a succession of interior explosions, even when in perfect condition, have failed to give satisfactory 35 results. If the armor-plate is light and the velocity of the shell high it may pass entirely through the vessel before exploding, piercing the armor-plate on both sides of 40 the vessel or its course may be deflected after entering the vessel so that it passes out through unarmored parts before exploding, or so that it explodes in a part of the vessel where the destructive effect of the 45 explosion is comparatively slight.

But fuses of the successive interior explosions and time-train types are rarely in perfect condition due to powder deterioration. The consequent impossibility of predetermining the time of the explosion, after 50 its initiating cause has been actuated, adds additional difficulties to those above enumerated.

This invention aims to obviate the difficulties above outlined, and those of similar

character, by assuring the explosion of the projectile within a negligible time after penetration, the construction of the fuse also being preferably such that upon the failure of the projectile to completely pierce the 60 armor-plate, it effects an explosion of the projectile on the maximum penetration therein, thereby overcoming the difficulty due to time-trains or successive internal explosions whereby the shell on failing to 65 pierce the plate may drop away and explode at such a distance therefrom as to be harmless. Such a construction offers the fuse a wide field of useful employment, for it renders projectiles equipped therewith also 70 especially destructive against earthworks and buildings, whether fired from guns or mortars or whether launched from aeroplanes or the like.

When a projectile strikes an armor-plate, 75 its velocity is suddenly diminished, and it continues to decrease as the projectile proceeds on its way through the plate; but upon 80 piercing the plate the projectile continues at a velocity substantially uniform though lower than that on impact, particularly if the armor plate is heavy. The deceleration on impact accordingly jumps to a high figure; it remains fairly constant during penetration, and as the projectile emerges, 85 decreases to its original value of slightly above zero. During flight there is of course a falling off of velocity due to air resistance but the rate is slight in comparison with the deceleration on impact and during penetration. If the projectile fails to pierce 90 the armor-plate and its diminished velocity is reduced to zero therein, the deceleration at this point also drops to zero. It is upon the above outlined decrease of deceleration 95 that the operation of our fuse depends.

The invention in its preferred form embraces means for storing up energy in a resilient medium on impact, which energy on decrease of deceleration is exerted to 100 move a part of the fuse into exploding contact with a detonator whereby the fuse is exploded and the projectile charge detonated. The creation of this energy is brought about by the movement of one of the fuse parts in 105 respect to the projectile due to the forward inertia of the part on impact. When the energy stored up in the resilient medium is sufficient to overcome the forward inertia of the movable part, unless otherwise re- 110

strained, it effects the explosion of the fuse as above indicated. This condition will be brought about when the projectile is brought to a stop in the armor-plate or other obstacle, or when or after it resumes a fairly uniform velocity after penetration thereof. It may also be brought about during penetration provided the character of the armor-plate or object is such as to cause the gradual falling off of deceleration. In the last-named case restraining means may if desired be provided and one form of such means is herein illustrated, the prime object being to prevent such a slow movement of the firing parts that their function is defeated. Whether with heavy or thin armor plates, the relative movement of the fuse part for arming is a function of the differential speed established; i. e. the difference between the speed which the projectile and the aforesaid part have at the moment of impact and the speed which the projectile has subsequent to such impact and up to the time, however short, that the fuse is placed in armed position.

We also provide safety means whereby the arming of the fuse is prevented prior to firing or launching, thus preventing accidental or premature explosion thereof. In connection with this phase of the invention, it should be noted that the principles above enunciated are not limited in their application to energizing the resilient medium for directly effecting the explosion of the fuse as distinguished from the use of such medium in releasing locking means whereby firing mechanism already energized will be brought into play.

In the accompanying drawings are illustrated fuses constructed in accordance with our invention, the forms shown being chosen for illustrative purposes, and it is to be understood that our invention is by no means confined thereto. In these drawings which form a part of this application:

Figure 1 is an axial-longitudinal section of a fuse embodying one form of our invention, illustrating the parts in normal position, i. e., the position of the parts of the fuse when in place in a projectile prior to firing or launching;

Fig. 2 is a cross-section on the line II-II of Fig. 1;

Fig. 3 is a cross-section on the line III-III of Fig. 1;

Fig. 4 is a cross-section on the line IV-IV of Fig. 1;

Fig. 5 is an axial-longitudinal section of the fuse showing the parts in the position they assume on impact of the projectile;

Fig. 6 is an axial-longitudinal section illustrating the firing position of the parts;

Fig. 7 is an axial-longitudinal section of a standard armor-piercing shell showing the fuse in side elevation mounted therein;

Fig. 8 is an axial-longitudinal section of another fuse, also embodying our invention, illustrating the parts in normal position, and corresponding in general with Fig. 1;

Fig. 9 is a cross-section on the line 70 IX-IX of Fig. 8;

Fig. 10 is a cross-section on the lines X-X of Fig. 8;

Fig. 11 is an enlarged detail of one of the locking balls and its supporting means, illustrating the same in cross-section;

Fig. 12 is a plan of one of the locking-lug springs illustrated in Fig. 8;

Fig. 13 is an axial-section of a fuse of the general type of Fig. 1, partly broken away, 80 illustrating a modification in the resilient medium actuating means;

Fig. 14 is an axial-section of a fuse of the general type of Fig. 8, partly broken away, 85 illustrating means for preventing creeping of the piston in flight and after impact and compression;

Fig. 15 is a diagram of the curves of velocity and negative acceleration or deceleration of a projectile on passing through a 90 section of heavy armor-plate; and

Fig. 16 is a diagram of the curves of work in foot-pounds done and effective pressure in pounds per square inch exerted by the piston on the resilient medium on the 95 forward stroke of the piston, air being employed as the resilient medium.

Referring first to the construction and operation of the fuse illustrated in Figs. 1 to 6, the base 15 of the fuse is externally 100 screw-threaded and shouldered and is thereby adapted for firm and proper fastening into the base plug 16 of a projectile 17 (see Fig. 7).

The base is hollow and at the rear constitutes a safety-chamber 20. It is internally 105 screw-threaded at its forward end to provide a mounting for the fuse-mechanism. Slightly to the rear of the screw-threaded portion, the base is internally weakened by an 110 annular groove 21, the purpose of which is to constitute a breakage zone so that, in case the fuse is subjected to stress beyond its strength on whipping or impact, the break will be localized at this point which is so selected that it will not prevent the normal 115 operation of the parts.

The fuse-mechanism comprises a hollow body 23 which, to reinforce the safety-chamber, extends rearwardly therein beyond the 120 breakage zone and abuts against an annular shoulder 24 formed near the rear of the chamber. On the exterior the body at its middle portion is formed with a series of strengthening longitudinal ribs 25-25 and 125 is inclosed by a thin metallic shell 26 thereby forming a series of booster-charge chambers 27 27 in which is contained a booster-charge of suitable explosive, for example, compressed crystalline T. N. T., indicated at 130

- 28 28; filling-apertures 29 29 being provided for the introduction and compression of the charge, the filling-apertures being subsequently closed with wax. The body at the 5 rear portion of the booster-charge chambers is reduced in thickness externally as at 30 30 so as to insure fracture at this place for detonating the booster-charge as hereinafter described.
- 10 A hollow sleeve 31 of general cylindrical shape is mounted in the body 23 and is adapted for forward motion therein. It is provided with a circumferential flange 32 which normally abuts against an annular shoulder 33 in the body, formed at the rear of an enlarged cylindrical portion therein. The forward part of the sleeve in advance of the circumferential flange is of a general conical contour being slightly tapered externally 20 toward the front.
- 15 A detonator 35 is firmly mounted upon the rear end of the sleeve and is normally positioned in the safety-chamber. The detonator is preferably of the usual compressed 25 fulminate-of-mercury type and may include a primer 37 suitably mounted in advance of the detonator at the rear of the sleeve. A No. 2 $\frac{1}{2}$ Winchester primer is an illustration of a suitable primer for this purpose and has 30 been used by us with successful results. The diameter of the detonator is slightly smaller than that of the bore of the body 23 so that it can be drawn forward therein without binding.
- 35 The sleeve is pierced by a series of radial openings 39 39 in which are carried clutch-lugs illustrated as balls 40 40. A suitably pointed firing-pin 41 of slightly less diameter than the interior of the sleeve, for clearance, 40 extends therein and is normally maintained in the position illustrated in Fig. 1 in relation to the sleeve by means of an annular groove 42 in which the balls are maintained by the inner walls of that portion of the body 45 normally opposite them. The diameter of the head of the firing-pin to the rear of the groove is slightly greater than that of the remainder of the pin to the front of the groove. The diameter of the enlarged portion 50 of the body in advance of the shoulder 33 is such that when the balls are brought opposite thereto they may be forced outward to clear the said groove in front and release the firing-pin for relatively rearward movement in the sleeve (see Figs. 5 and 6); but the enlarged head of the firing-pin prevents the latter from being drawn forward out of the sleeve, permitting the balls to fall into the space between the firing-pin and the detonator. 55
- 60 A piston 44 is suitably mounted on the forward end of the firing-pin. The piston is hollow at the rear and if desired is further lightened by a series of apertures 45 46, and 65 it is slightly crowned on its forward face to prevent its bearing edges from becoming upset. It reciprocates in a hollow cylinder 46, which is screwed on the forward portion of the body 23 diametrically reduced for this purpose, and forms a close fit therein so that the space between the face of the piston and the forward end of the cylinder forms an air chamber. Escape of air therefrom may be further deterred by a film of oil between the piston and the cylinder if found necessary. 70
- The sleeve 31, firing-pin 41 and piston 44 are normally locked in their rear position by the following means:
- 75 In the forward end of the body 23 which is slightly enlarged internally for this purpose is firmly mounted a hollow lock-carrier 48 which is of a general cylindrical contour and through which extends the firing-pin. It is pierced by a plurality of radial apertures 49 49, two being illustrated diametrically opposite each other, in which are held a corresponding plurality of locking-lugs 50 50, normally pressed inwardly by a spring-ring 51, but adapted to move outwardly under the action of a proper amount of centrifugal force. The firing-pin is formed with an annular groove 53, preferably square shouldered, which in the normal position is in line with the apertures 49 49 80 and into which the lugs 50 50 are pressed in locking engagement as above indicated. 85
- 85 The lock-carrier extends forwardly from its locking apertures and normally abuts against the rear interior face of the piston, 90 its interior being slightly flared outwardly. The rear of the lock-carrier is made in the form of a cylindrical chamber of a diameter slightly in excess of that of the forward portion of the sleeve 31 for clearance. 95
- 90 A retarding-ring 55 of copper or similar pliable metal is mounted at the rear of the lock-carrier and held thereby against an annular shoulder 56 in the forward portion of the body 23. The retarding-ring is 100 beveled internally toward the rear and its exterior diameter is slightly less than that of the body opposite thereto, its interior beveled portion being of dimensions corresponding with the middle third of the conical 105 portion of the sleeve 31 so that the sleeve on entering the retarding-ring must expand it outwardly. See Figs. 5 and 6. The bevel of the retarding-ring and the taper of the forward portion of the sleeve 31 should 110 preferably be no greater than the wedging angle, with the result that when the sleeve has assumed the position of Figs. 5 and 6 it is firmly maintained there by friction. The depth of the chamber in the rear of the 115 lock-carrier is here illustrated as being such as to prevent the sleeve 31 from seating therein and becoming jammed on the firing-pin. 120
- 125 These parts are so disposed and of such 130

dimensions that when the circumferential flange 32 of the sleeve rests against the retarding-ring 55, with a forward movement of the firing-pin, the detonator 35 is withdrawn from the safety-chamber and is located opposite the reduced portions 30 30 of the body (see Figs. 5 and 6); further, so that the radial openings 39 39 of the sleeve are then opposite the enlarged portion of the body in advance of the shoulder 33 therein, whereby the locking-lugs or balls 40 40 are released as above indicated from locking engagement with the annular groove 42 of the firing-pin, but not until the firing-pin has been moved from the possible range of the detonator on its forward travel; and finally so that the permissible forward piston travel is less than the forward sleeve travel, with the result that the annular groove 42 will then be sufficiently at the rear of the radial openings 39 39 for the locking-lugs or balls 40 40 to rest on the sides of the firing-pin, with the pointed end of the latter at the desired distance in front of the primer 37. This latter characteristic, however, is optional and not essential to the unlocking of the two members.

The operation of the fuse above described will now be discussed:

When a projectile in which the fuse is mounted is fired or launched there is no rearward movement of any of the parts due to the setback. The stress of the setback on the sleeve 31 is borne by the shoulder 33 and circumferential flange 32, and that on the firing-pin and piston by the forward end of the lock-carrier against which the rear face of the piston normally abuts as aforesaid.

The centrifugal type of lock herein shown is especially adapted for gun-propelled projectiles, being released by the rapid rotation of the projectile on its axis due to the rifling of the gun barrel. In the form illustrated the locking-lugs by reason of their opposite disposition assure the locking of the firing-pin against accidental release, as the outward movement of either one alone does not unlock the firing-pin. Obviously this result is not dependent upon employing merely two locking-lugs oppositely disposed. They further assure against accidental discharge on a nose drop such as might occur in transportation and handling.

Upon firing the projectile the locking-lugs 50 50 move outwardly, deforming the spring-ring 51 into an oval shape and assuming the position indicated in Figs. 5 and 6 during flight, and thus release the firing-pin. This unlocking of the firing-pin is the only relative movement of parts during flight, except for a slight forward creep of the piston, firing-pin, and sleeve, due to the small retardation caused by air resist-

ance. This is soon balanced by the increase of pressure in the cylinder.

Upon or as a result of impact of the projectile with the object struck and the retardation occasioned thereby, the sleeve 31, firing-pin 41 and piston 44, due to their inertia, plunger forward in the fuse. The piston compresses the air in the chamber in advance thereof and comes to rest at or near the inner end of the cylinder 46. The sleeve 31 travels with the piston and the forward tapering end wedges into the retarding-ring 55, expanding the same and retarding the movement of the sleeve to cushion the blow on the detonator and prevent premature explosion, but because of the sleeve's longer path of travel than the piston, its forward movement continues and the locking-lugs or balls 40 40, now inside the inwardly expanded portion of the body, ride out of the annular groove 42, thereby unlocking the sleeve and firing-pin, and permitting the sleeve to advance until it seats against the retarding-ring with the lugs or balls resting on the sides of the firing-pin as aforesaid.

Continuing the illustration with an armor-piercing projectile and referring to Fig. 15, it is there seen that as the projectile strikes and penetrates the armor-plate its velocity drops fairly uniformly from about 1700 ft. per second to 300 ft. per second, and that the deceleration of the shell goes from slightly above zero to approximately 14,000,000 ft. per second where it remains during the penetration of the armor-plate, these figures being based on calculation and experiment with a twelve-inch projectile fired with a standard charge through a twelve-inch armor-plate, and being of course employed for illustrative convenience only. Further, that upon the projectile emerging from the plate, it resumes a substantially uniform velocity of about 300 ft. per second, and its deceleration instantly drops to its original value of slightly above zero.

During this drop in velocity the inertia of the piston 44 keeps it in its forward position against the effort of the compressed air to force it rearwardly. As soon, however, as the projectile on piercing the armor-plate resumes a uniform velocity, or on failing to pierce the same, comes to rest therein, the deceleration, and consequently the forward inertia of the piston, drops off, whereupon the compressed air in advance of the piston forces the piston and firing pin rearwardly and the firing pin explodes the primer 37. It will be remembered that the fulminate-of-mercury detonator is at this time firmly held against rearward motion by the friction between the retarding-ring and the tapering forward end of the sleeve 31. (See Fig. 6). The explosion of the primer ignites

the fulminate of mercury in the detonator 35, causing its explosion, which in turn bursts the inner walls of the booster-charge chamber at the reduced portions 30 30 igniting the booster-charge, which on explosion bursts the inclosing metallic shell 26 and detonates the main explosive charge of the projectile.

In the case of a thin armor plate where 10 the drop of velocity of the projectile is slight, it should readily be seen that the movable parts of the fuse may not have moved forward to their arming position until a fraction of time after the projectile 15 has assumed a substantially uniform velocity after penetration. But the forward movement of the parts during flight, heretofore referred to, by lessening the distance of travel of the parts after impact cuts down 20 this delay.

Further discussion of the theory of operation is postponed until the modifications illustrated in Figs. 8 to 13 have been presented.

In Figs. 8 to 12 it will be observed that 25 the fuse generally and many of the parts are the same as in the construction of Figs. 1 to 6, and the same reference numerals are accordingly applied. The body 123 of the 30 fuse-mechanism contains some modifications over the corresponding part 23 in the previous figures. The filling apertures 29 29 for the booster-charge are omitted and instead the rear portion of the body which 35 extends into and reinforces the safety-chamber is made in two parts, comprising an outer flanged sleeve 60 screwed onto the rear reduced portion 61 of the fuse-body. These parts are assembled after the booster-charge 40 has been packed in the booster-charge chamber and additional facilities for equally packing the booster-charge are thereby provided.

Furthermore the booster-charge chamber 45 127 differs from the plurality of chambers of the preceding figures in that the reinforcing ribs 125 125 of the fuse body are tapered forwardly so that the booster-charge is continuous around the chamber 50 and will be simultaneously detonated under all conditions.

The reduced portions of the fuse-body 130 130 are made lighter than in the previous case and the detonator 35 carries a larger 55 quantity of fulminate of mercury. This insures the bursting of the reduced portions of the fuse-body on the explosion of the detonator in case the booster-charge is packed extraordinarily hard.

The firing-pin 141 is not locked against 60 forward motion in respect to the sleeve 31 by the lugs or balls 40 40, but is cut away at the rear of the balls as at 62 so as to be free therefrom. The balls are prevented

from dropping inwardly in case of the withdrawal of the firing-pin by the radial openings 139 139 in the sleeve 31 being partially closed on the inside. (See Fig. 11.) This modification is chiefly of importance in assembling.

The piston 144 is made without the lightening apertures 45 45 and is otherwise considerably heavier than that of the previous figures. The cylinder 146 differs only in providing clearance for the locking means 75 which are also somewhat altered in construction though not in function.

The lock-carrier 148 is not flared at the front and consequently offers a larger abutting surface to the rear of piston for taking up the setback on the piston and firing-pin. The cavity at the rear of the lock-carrier is of a slightly less depth than in the case of the previous construction so that the forward tapered end of the sleeve 31 seats 80 against the bottom of the cavity at the same time that the annular flange 32 seats against the retarding-ring 55 on the forward movement of the sleeve. This construction is intended to obviate any possible crushing of 85 the retarding-ring at that time.

The lock-carrier is provided with two circumferential flanges 64 64 in line with the respective edges of the locking-lug apertures 49 49. These are slotted diametrically as at 95 65 65 and afford a mounting means for two bent leaf-springs 67 67, which are located between the flanges and which are provided with lugs 68 68 that lie in the slots 65 65. These leaf-springs are compressed and are 100 kept in engagement with the locking-lugs 50 50 by means of a flanged metallic ring 70 which is placed over the circumferential flanges 64 64 and maintained in position when the lock-carrier is screwed home by the 105 flange of the ring held between the rear flange 64 and the front end of the fuse-body.

The square-shouldered annular groove 53 in the firing-pin of the previous construction is also changed. The firing-pin is reduced in size in line with the locking-lugs, and slightly to the rear thereof is considerably enlarged as at 72, the enlarged portion being square-shouldered and affording additional strength against shearing on accidental nose-drop. The reduced portion of the firing-pin extends somewhat to the front of the locking-lugs where it flares out into a flange 73 which abuts against the rear of the piston. Extending the reduced portion 120 beyond the locking-lugs in this manner assures against jamming of the lugs by the setback.

The general operation of the construction of Figs. 8 to 12 does not differ materially 125 from that of the construction of Figs. 1 to 6 and will be readily understood without repetition.

- In Fig. 13 is illustrated an alternative form of resilient medium to effect rearward propulsion of the firing-pin. Aside from this the parts of the fuse are identical with those illustrated in Figs. 1 to 6, except as now indicated. In this construction the piston 44 and the extreme forward portions of the lock-carrier 48 are omitted. The firing-pin 41 terminates in front in a plunger 244, against the forward face of which is seated a coiled spring 80 normally slightly compressed and seated at its opposite end against the inner face of the cylinder 46 which is provided with a plunger-stop 82.
- 10 The function of the coiled spring 80 is the same as that of the compressed air and its operation is similar, except that there will be less creepage forward of the fuse parts during flight. It is compressed on or as a result of impact by the movable parts due to their inertia and is released after arming when the velocity of the movable parts become the same as that of the projectile. In case of heavy armor plate this will take place when the velocity of the projectile after impact assumes a substantially constant value or becomes zero: In case of a thin armor plate the arming may be slightly delayed.
- 20 Continuing now with the interrupted discussion of the operation of our invention, the forces which determine the operation of the piston to effect the compression of the resilient member and a rearward stroke of the piston to cause an explosion are illustrated in Fig. 16. The abscissæ represent the travel of the piston from its original position in thirty-seconds of an inch. The ordinates represent respectively the effective pressures in pounds per square inch developed in the resilient medium (specifically air) by the piston on its forward stroke, and the work in foot-pounds done on the said medium by the piston. Disregarding the effects of friction, this may also be said to represent the work done by the resilient medium on the piston during the return stroke thereof. In determining these curves the diameter of the piston was assumed as one inch, with a maximum possible travel or $\frac{1}{4}$ of an inch.
- 30 This figure shows clearly that the further the piston moves on its forward stroke, the higher will be the resultant pressure in the chamber and the greater will be the work done on the resilient medium. Consequently the further the piston moves forward the greater will be its striking energy on the return stroke. It has been experimentally determined that the work necessary to pierce the primer above mentioned is approximately .5 foot-pound; hence it is necessary to drive the piston forward a distance of at least $\frac{1}{2}$ of an inch to secure this result.
- 40 The distance that the piston will be driven

forward depends upon the forward inertia force set up therein, which in turn depends both upon the deceleration of the projectile upon impact and during penetration, and upon the weight of the piston. Hence if 70 it is desired to make the fuse extremely sensitive, so that it will function after impact with very thin plating, with consequently slight deceleration, this may be accomplished by providing a comparatively heavy piston, 75 in order to develop a greater forward inertia force upon a given deceleration corresponding with that in hand. Such a piston is illustrated in Figs. 8 and 14. If on the contrary it is desired to make the fuse comparatively insensitive, so that it will be exploded only by penetrating armor-plate of considerable thickness, a comparatively light piston may be employed.

An example of a case wherein an insensitive fuse might be extremely valuable would be in conjunction with a mortar projectile used in coast defense work. This projectile descends upon the deck of a ship at an extremely high angle. The vitals of a ship, 90 such as engines, boilers and magazines are carried below a protective deck of comparatively heavy plating situated at or near the water line. Above this are other decks of much lighter plating. If a sensitive fuse 95 were used in this type of projectile the latter would be exploded shortly after penetration of the first light deck and consequently only fragments of the projectile would reach the heavy protective deck without penetration thereof. If, however, a comparatively insensitive fuse is employed, the projectile will be exploded only after passing through the heavy protective deck and hence the explosion will occur in the vitals of the ship 100 where its effect would be greatest.

Furthermore, it will be seen from an inspection of Fig. 16 that if at any time the deceleration during penetration decreased very gradually, the forward inertia force in 110 the piston would be correspondingly decreased and hence the pressure of the resilient medium would maintain itself constantly equal to this decreasing inertia force. The result of this would be that the piston and 115 firing-pin would be eased backward until the firing-pin rested upon the primer without explosion thereof. This contingency, which is unusual, would probably arise when the object penetrated is of such character 120 as to offer progressively decreasing resistance to the projectile. It may be taken care of by such a construction as is illustrated in Fig. 14.

In Fig. 14, which illustrates the forward 125 portion of the construction of Figs. 8 to 12, the piston 144 is shown with a circumferential groove 85 in which is fitted a round-sectioned piston-ring 86, which is split and possesses a certain amount of elasticity. 130

When the piston is in its normal position, the one illustrated, the piston-ring engages a shallow annular and preferably rounded groove 87 formed on the interior of the cylinder 146. Another and much deeper annular groove 88, also preferably rounded, is situated in the interior of the cylinder at such a point that when the piston is at its maximum forward position, indicated by the broken line 89, the piston-ring will engage therewith. The depth of this groove is slightly less than the radius of the section of the piston-ring.

This construction will operate as follows:

15 When the projectile is fired, the piston-ring remains seated in the shallow groove 87, thereby preventing the piston from creeping forward in flight due to the slight deceleration of the projectile caused by air resistance. As the groove 87 is extremely shallow, however, it offers only slight resistance to the forward movement of the piston upon impact with an obstacle. Upon impact the piston is forced fully forward, and the piston-ring engages with the deep groove 88, thus locking the piston against rearward creepage. At this time the forward inertia force of the piston will balance the air pressure, but as the deceleration grows less the 25 inertia force will correspondingly decrease. When the difference between the forward inertia force and the pressure of the resilient medium has reached a certain predetermined amount, dependent in part on the resiliency 30 of the piston-ring and the curvature or bevel of the rear face of the groove 88, the resultant rearward pressure will force the piston-ring from the groove 88 into the groove 85 and release the piston, which then 35 plunges to the rear under full head of the resilient medium and pierces the primer, causing explosion of the fuse.

It will be observed that the locking means illustrated in Fig. 16 do not interfere with 45 the operation of the fuse under what may be considered normal conditions, i. e., those in which the projectile either penetrates armor-plate or other defensive obstacle or is brought to rest therein, under fairly uniform deceleration prior to piercing or stoppage, in the event of either of which there is an abrupt drop in deceleration. In case the initial deceleration has not been sufficient to bring about a maximum forward 50 travel and locking of the piston obviously the locking means, except in so far as they prevent creeping during flight, are inert and may be disregarded. In case the piston is moved to its forward limit of travel, the 55 reduction of deceleration due to complete penetration or stoppage of the projectile will cause the resultant rearward pressure on the piston to become so large that the piston is at once released.

65 The foregoing detailed description has

been given for clearness of understanding and no undue limitation should be deduced therefrom, but the appended claims should be construed as broadly as permissible in view of the prior art.

What we claim as new and desire to secure by Letters Patent of the United States is:

1. In a fuse for a high explosive projectile, the combination of a booster charge, a firing element embodying a detonator for causing the explosion of the booster charge and brought into action by a decrease of the deceleration of the projectile, means whereby the booster charge and detonator are normally maintained in a non-explosive relation, and means for establishing explosive relation between the booster charge and detonator prior to said action of the firing element.

2. In a fuse for a high explosive projectile, the combination of a booster charge, a firing element embodying a detonator for causing the explosion of the booster charge and comprising a member moved to effect the said explosion by a decrease of the deceleration of the projectile, means whereby the booster charge and detonator are normally maintained in a non-explosive relation, and means for establishing explosive relation between the booster charge and detonator prior to said action of the firing element.

3. In a fuse for a high explosive projectile, the combination of a booster charge, relatively movable coöperating members one of which embodies a detonator for causing the explosion of the booster charge, said members being brought into coöperative relation to effect said explosion by a decrease of the deceleration of the projectile, means whereby the booster charge and detonator are normally maintained in a non-explosive relation, and means for establishing explosive relation between the booster charge and detonator prior to said movement of said members.

4. In a fuse for a high explosive projectile, the combination of a booster charge, a firing element embodying a detonator for causing the explosion of the booster charge, said firing element being brought into operative position by the deceleration of the projectile on impact with an object during flight, means for effecting a movement thereof to cause said explosion dependent in operation upon the character of the said object, means whereby the booster charge and detonator are normally maintained in a non-explosive relation, and means for establishing explosive relation between the booster charge and detonator prior to said movement.

5. In a fuse for a high explosive projectile, the combination of a booster charge, a firing element comprising a detonator and a firing pin normally interlocked therewith

- for causing the explosion of the booster charge, said firing element being actuated on a decrease of deceleration of the projectile to cause said explosion, and means for restraining the action of the firing element prior to a predetermined decrease of deceleration.
6. In a fuse for a high explosive projectile, the combination of a booster charge, a 10 detonator for causing the explosion of the booster charge, a member movable for effecting said explosion, means including a resilient element energized on impact with an obstacle during flight for causing a subsequent 15 firing movement of said member, means whereby the booster charge and detonator are normally maintained in a non-explosive relation, and means for establishing explosive relation between the booster 20 charge and detonator prior to said firing movement.
7. In a fuse for a high explosive projectile, the combination of a booster charge, a detonator for causing the explosion of the 25 booster charge, a detonator carrier, a member movable for effecting the said explosion, said member being normally interlocked with the detonator carrier and released therefrom after impact with an obstacle 30 during flight, means including a resilient element energized on said impact for causing a subsequent firing movement of said member, and means for restraining such movement of said member prior to a predetermined decrease of deceleration.
8. In a fuse for a high explosive projectile, the combination of a booster charge, a detonator for causing the explosion of the booster charge, a member movable to a position 40 preparatory to a movement therefrom for effecting said explosion, means operative on deceleration of the projectile due to impact with an obstacle during flight to effect the preparatory movement of said member, a resilient element to resist said movement and to effect reversal in the direction thereof whereby the said explosion is brought about, means whereby the booster charge and detonator are normally maintained in a non-explosive 45 relation, and means for establishing explosive relation between the booster charge and detonator prior to the firing movement of said member.
9. In a fuse for a high explosive projectile, the combination of a booster charge, a detonator for causing the explosion of the booster charge, a detonator carrier, a firing member normally interlocked therewith and released after impact with an obstacle during flight, and means operative on deceleration 55 of the projectile due to said impact for placing the fuse in condition for subsequent movement of the firing member for effecting said explosion, said means comprising a re-
- silient medium compressed during such deceleration.
10. In a fuse for a projectile, the combination of a firing member and means operative on deceleration of the projectile due to impact with an obstacle during flight for placing the firing member in condition for subsequent movement thereof for firing, said means comprising a piston operatively connected with the firing member, and a cylinder in which the piston is carried and which permits reciprocal motion of the piston therein, the cylinder being normally under atmospheric pressure and being closed at one end and co-operating with the piston to form a compression chamber.
11. In a fuse for a high explosive projectile, the combination of a booster charge, a detonator for causing the explosion of the booster charge and normally in non-explosive relation therewith, means actuated on impact of the projectile during flight with an obstacle occasioning deceleration thereof for placing the fuse in operative condition, and means for effecting the said explosion on the subsequent decrease of deceleration of the projectile.
12. In a fuse for a high explosive projectile, the combination of means actuated on impact of the projectile during flight with an object occasioning deceleration thereof for placing the fuse in operative condition, locking means whereby explosion of the fuse is prevented prior to said impact, and means embodying a booster charge and a detonator therefor normally in non-explosive relation therewith for effecting the explosion of the fuse on a subsequent decrease of deceleration.
13. In a fuse for a high explosive projectile, the combination of a booster charge, a detonator for causing the explosion of the booster charge and normally in non-explosive relation therewith, a member capable of longitudinal movement in the fuse and movable forwardly on impact of the projectile, means energized by said forward movement of the member to move it rearwardly by reason of a subsequent decrease of the deceleration of a projectile whereby the said explosion is brought about, and means for establishing explosive relation between the booster charge and detonator prior to said firing movement.
14. In a fuse for a high explosive projectile, the combination of a booster charge, a detonator for causing the explosion of the booster charge and normally in non-explosive relation therewith, a part coacting with the detonator and capable of movement relative in respect thereto after impact of the projectile, resilient means placed under compression by movement of one of the said parts upon a reduction of velocity of the

projectile on impact and causing retrograde movement of such part by reason of a subsequent decrease of deceleration of the projectile whereby the said explosion is brought about, and means for establishing explosive relation between the booster charge and detonator prior to said firing movement.

15. In a fuse for a high explosive projectile, the combination of a booster charge, a detonator for causing the explosion of the booster charge and normally in non-explosive relation therewith, a member capable of forward movement in respect to the projectile on the reduction of the velocity thereof on impact, means for resisting such relative forward movement of the member and converting the kinetic energy thereof into energy serving to move the member rearwardly by reason of a subsequent decrease of deceleration of the projectile whereby the said explosion is brought about, and means for establishing explosive relation between the booster charge and detonator prior to said firing movement.

25. 16. In a fuse for a high explosive projectile, the combination of a booster charge, a detonator for causing the explosion of the booster charge and normally in non-explosive relation therewith, a member movable in respect to the projectile on deceleration thereof and movable in a reverse direction in respect thereto to effect the said explosion by reason of a subsequent decrease of deceleration of the projectile, and means for establishing explosive relation between the booster charge and detonator prior to said firing movement.

17. In a fuse for a high explosive projectile, the combination of a booster charge, a detonator for causing the explosion of the booster charge and a carrier therefor, a firing pin, said detonator carrier and firing pin being movable forwardly on impact of the projectile, means for holding one of said members in its forward position, and means for subsequently causing retrograde movement of the other member after impact for effecting said explosion.

18. In a fuse for a projectile, the combination with a detonator and its carrier, of a relatively movable firing pin, a lock normally connecting the parts for movement together in one direction, and means for releasing the lock after firing.

55. 19. In a fuse, the combination of a detonator, a detonator carrier, a relatively movable firing pin therein, means positioned in one of these parts, and means co-operating therewith for preventing firing engagement of the detonator and firing pin prior to a predetermined relative movement of the said means.

20. In a fuse for a projectile, the combination with a detonator and its carrier,

of a relatively movable firing pin, means positioned in one of these parts for preventing firing engagement of the detonator and firing pin prior to a predetermined movement of the said parts in the same direction, and means for thereafter releasing said parts for firing engagement after impact.

21. In a fuse, the combination of a detonator, a detonator carrier, of a relatively movable firing pin therein, means positioned in one of these parts, and means co-operating therewith for preventing firing engagement of the detonator and firing pin prior to a predetermined relative movement of the said means, and resilient means for thereafter bringing about said engagement.

22. In a fuse, the combination of a detonator and its carrier, a relatively movable firing pin, means positioned in one of these parts for preventing firing engagement of the detonator and firing pin prior to a predetermined movement of said parts in the same direction, resilient means compressed by said movement, and means for thereafter releasing the detonator carrier and firing pin for firing engagement, said firing engagement being brought about by said compressed resilient means.

23. In a fuse, the combination with a detonator and its carrier, of a relatively movable firing pin, a lock normally connecting the parts for movement together in one direction, and means for releasing the lock after a predetermined conjoint movement of the connected parts.

24. In a fuse for a projectile, the combination of a detonator and its carrier, a relatively movable firing pin, a lock between the parts, and means actuated by impact of the projectile with an obstacle during flight for releasing the lock.

25. In a fuse for a projectile, the combination of a detonator and its carrier, a firing pin relatively movable in respect to the detonator, a lock between the carrier and the firing pin whereby contact of the firing pin with the detonator is prevented on impact of the projectile, and means for subsequently releasing such lock to permit the explosion of the detonator.

26. In a fuse for a high explosive projectile, the combination of a booster charge, a detonator, locking means for normally maintaining the detonator in a position of safety in respect to the booster charge and which are released prior to impact, means for holding the detonator in operative position after movement thereof to such position, and a firing mechanism for the detonator energized by deceleration of the projectile, and movable to effect an explosion on a subsequent decrease of the deceleration of the projectile.

27. In a fuse for a high explosive projectile, the combination of a booster charge, a detonator normally positioned in a place of safety in respect to the booster charge, 5 a movable member connected therewith for moving the detonator into operative position, a stop for controlling the movement of the said member and holding the same in said operative position, and a firing mechanism for the detonator energized by deceleration of the projectile, and movable to effect an explosion on a subsequent decrease of the deceleration of the projectile.
28. In a fuse, the combination with a detonator normally positioned in a place of safety, of a member connected therewith for moving the detonator into operative position, a stop for there arresting the said member, a relatively movable firing pin, a 15 stop for arresting the movement of the firing pin, means for normally locking the movable member and firing pin for movement together, and means for releasing the same upon a predetermined conjoint movement thereof and prior to the arrest of the firing pin.
29. In a fuse, the combination with a detonator normally positioned in a place of safety, of a member connected therewith for 20 moving the detonator into operative position, a stop for there arresting the said member, a relatively movable firing pin, a stop for arresting the movement of the firing pin prior to the arrest of the detonator, 25 means for normally locking the movable member and firing pin for movement together, and means for releasing the same upon conjoint movement thereof and prior to the arrest of the firing pin.
30. In a fuse for a projectile, the combination with a detonator carrier and a firing pin movable lengthwise of the fuse, of means for locking the parts together for forward movement on impact of the projectile and releasing such parts from each other 35 on such movement, and means for holding one of the parts against movement rearwardly after impact.
31. In a fuse for a projectile, the combination with a detonator carrier and a firing pin movable lengthwise of the fuse, of means for locking the parts together for forward movement on impact of the projectile and for releasing such parts from each other on such movement, means for holding one of the parts against movement rearwardly after impact, and means for causing rearward movement of the other part after impact.
32. In a fuse for a projectile, the combination with a detonator carrier and a firing pin movable lengthwise of the fuse, of means for locking the parts together for forward movement on impact of the projectile.
33. In a fuse for a projectile, the combination with a detonator carrier and a firing pin movable lengthwise of the fuse, of means for normally locking the parts against movement and releasing them prior to impact of the projectile, means for locking the parts together for forward movement on impact and for releasing such parts from each other on such movement, means for holding one of the parts against movement rearwardly after impact, and means for causing rearward movement of the other part after impact.
34. In a fuse for a projectile, the combination with a detonator carrier and a firing pin movable lengthwise of the fuse, of means for normally locking the parts against movement and releasing them prior to impact of the projectile, means for locking the parts together for forward movement on impact and for releasing such parts from each other on such movement, means for holding one of the parts against movement rearwardly after impact, and means for causing rearward movement of the other part after impact.
35. In a fuse for a projectile, the combination with a detonator carrier and a firing pin movable lengthwise of the fuse, of means for normally locking the parts against movement and releasing them prior to impact of the projectile, means for locking the parts together for forward movement upon impact and for releasing such parts from each other on such movement, means for holding one of the parts against movement rearwardly after impact, and means for causing rearward movement of the other part after impact.
36. In a projectile, the combination of an explosive charge, and a fuse therefor comprising a detonator normally located in a safe position in respect to the charge, but moved into operative relation with said charge on deceleration of the projectile, and a firing mechanism for the detonator energized by deceleration of the projectile, and movable to effect an explosion on a subsequent decrease of the deceleration of the projectile.
